(57) **CLAIM**

An ornamental design for a hydraulic manifold port plug as shown.

DESCRIPTION

FIG. 1 is a perspective view of the hydraulic manifold port plug.

FIG. 2 is an alternative perspective view of the hydraulic manifold port plug, the view of FIG. 2 being opposite the view of FIG. 1.

FIG. 3 is a top plan view of the hydraulic manifold port plug.

FIG. 4 is a side view of the hydraulic manifold port plug.

FIG. 5 is an alternate side view of the hydraulic manifold port plug, the view of FIG. 5 being opposite the view of FIG. 4; and,

FIG. 6 is a bottom plan view of the hydraulic manifold port plug.

The broken line inner circles appearing in FIGS. 3 and 6 do not constitute a part of the claimed design.
